UNITED STATES PATENT OFFICE.

CHARLES N. WINSHIP, OF WAKEFIELD, MASSACHUSETTS, ASSIGNOR TO WINSHIP, BOIT & CO., A COPARTNERSHIP CONSISTING OF CHARLES N. WINSHIP AND ELIZABETH E. BOIT, BOTH OF WAKEFIELD, MASSACHUSETTS.

UNDERGARMENT.

Application filed March 13, 1926. Serial No. 94,587.

This invention relates to ladies' underwear and is especially concerned with garments of the combination type designed to be worn instead of a shirt. Such garments are sold 5 under a great variety of names and they are usually provided with very short legs and have a closed crotch. Heretofore the majority of garments of this type have been made from cotton knit goods and the problem 10 of making a well fitting garment has been greatly simplified by the fact that the fabric from which they are made is extremely elastic. When such garments are manufactured from a much less elastic material, such as knit silk 15 or rayon, this problem becomes more troublesome, and the undergarments usually made from the latter materials have not had the well fitting characteristics of the cotton garments. The present invention deals with this 20 problem and it aims to devise an undergarment suitable for manufacture from silk, rayon, and other relatively inelastic fabrics, which will have the seat and leg room necessary for the comfort and convenience of the 25 wearer, while at the same time being shapely and well fitting. It is also an object of the invention to devise a garment having these advantages which can be manufactured economically.

30 The nature of the invention will be readily understood from the following description when read in connection with the accompanying drawings, and the novel features will be particularly pointed out in the appended 35 claim.

In the drawings,

Figures 1 and 2 are perspective views showing the front and rear, respectively, of a garment constructed in accordance with this 40 invention;

Figs. 3, 4 and 5 are plan views showing the more important parts from which the garment shown in Figs. 1 and 2 is made; and

Fig. 6 is a plan view showing the crotch 45 construction of the garment.

Referring first to Figs. 1 and 2 it will be seen that the garment consists chiefly of a front section 2, which forms the greater part of the body of the garment, a rear panel 3, and a front gusset 4. The parts from which this garment is made are clearly shown in Figs. 3, 4 and 5. The front section 2 is approximately rectangular in form and has a slit 5 extending for a considerable distance

upwardly from about the middle of the lower edge thereof. The gusset 4 is sewed to the opposite edges of the slit 5. The lateral edges of the back panel 3 are united to the opposite lateral edges of the front section 2 by seams 6 and 7, Fig. 2, which lie at the back 55 of the garment. Formed in the central part of the lower edge of the gusset 4 is a notch 8 while a similar notch 9 is formed in the lower edge of the back panel 3, and these notched portions are united in the crotch by 60 a seam 10, Fig. 6. Two strips of edge binding 11 and 12, preferably consisting of tubular knit fabric of the same material as the main body of the garment, are stitched to the lower edges of the parts 2, 3 and 4 where 65 they will form the edges of the very short legs with which the garment is provided. The upper edge of the garment is hemmed or finished in any suitable manner, and shoulder straps 14 are secured to this edge. 70

It will be observed that the back panel 3 is relatively narrow from the top down to the region of the waist, and that it widens very rapidly from the waist to the lower edge thereof. This construction is of value in giving the garment the desired fit, and, combined with the fact that the lower edge portions 15 and 16, Fig. 5, of the panel extend 75 downwardly toward each other from the opposite lateral edges, provides the necessary 80 fullness in the seat to make the garment comfortable and convenient. A shapely well fitting garment thus is provided which has ample room for comfort, without, at the same time, being baggy or having an undesirable 85 excess of material at any point. Since the entire body of the garment consists of three pieces, the manufacture of the garment requires the handling of only a very few parts. The number of seams to be run also is reduced. Usually the parts 2, 3 and 4 are cut 90 from tubular knit fabric, and the shape of the parts is such that the goods can be cut without excessive waste. The garment can therefore be manufactured economically. 95

While I have herein shown and described a preferred form of the invention, it will be evident that considerable variation in construction of the garment is permissible within the limits of the invention. 100

Having thus described my invention, what I desire to claim as new is:

A lady's undergarment comprising a front

section forming the greater part of the body of the garment, said front section being of approximately rectangular form with a slit extending for a considerable distance upwardly from the central part of the lower edge thereof, a tapered gusset sewed to the opposite edges of said slit, a back panel sewed to the opposite edges of said front sec-

tion, said panel being relatively narrow at its top and waist and widening rapidly below the waist, the lower edges of said gusset and back panel being united in the crotch of the garment, and the lower edges of said panel extending from opposite lateral edges thereof downwardly toward each other to the crotch. 10

CHARLES N. WINSHIP.
